UNITED STATES PATENT OFFICE.

FRANCIS W. MURPHY, OF BUFFALO, NEW YORK.

AMUSEMENT DEVICE.

No. 892,070.

Specification of Letters Patent. Patented June 30, 1908.

Application filed August 3, 1906. Serial No. 328,987.

To all whom it may concern:

Be it known that I, FRANCIS W. MURPHY, a citizen of the United States, residing at Buffalo, in the county of Erie and State of New York, have invented a new and useful Improvement in Amusement Devices, of which the following is a specification.

This invention relates to that class of amusement devices which comprise a vehicle or body for receiving passengers or patrons and means for producing the illusion that the vehicle is moving forward.

The object of this invention is to produce an amusement device of this character in which the movements of a sub-marine boat or air ship are simulated so as to give the occupants the impression that they are being transported under water or through the air.

In the accompanying drawings consisting of three sheets: Figure 1 represents a vertical longitudinal sectional elevation of a submarine boat or air ship embodying my invention. Fig. 2 is a fragmentary longitudinal section of the same, on an enlarged scale, showing the mechanism for producing the rocking or tilting movement of the body. Fig. 3 is a bottom plan view thereof partly in section. Figs. 4 and 5 are vertical transverse sections in lines 4—4 and 5—5 Fig. 2, respectively.

Similar letters of reference refer to like parts in the several figures.

A represents the body of the car or vehicle or compartment which is adapted to receive the patrons which are to be entertained. The same is preferably constructed in the shape of a cigar, as shown in the drawings, so as to have the general appearance of a submarine boat or air ship from the interior of the body. Any suitable means may be provided to permit the passengers to enter and leave the body, that shown in the drawings consisting of a doorway or opening *a* formed at the rear end of the body and a gang-plank *B* pivoted at one end to the sill of the doorway and resting at its opposite end on a stationary platform *b*. On the inside of the body seats *c* are provided for the passengers and in the side walls of the body, windows or port holes *d* are provided outside of which the effects may be produced in imitation of those which would be experienced in traveling under water such as the passing of fishes or sub-marine vegetation. If it is desired to imitate the effects which would be experi-

enced in an airship passing through the air, various illusions may be produced such as the movements of clouds and birds past the outside of the windows.

At the front end of the interior of the compartment or body is arranged an upright screen *E* upon which the scenes or moving pictures appropriate to the occasion may be projected by a picture machine *e* mounted on an elevated platform or stage *F* near the rear end of the body. For heightening the illusion of passing under water or through the air, pictures harmonizing with this idea may be thrown upon the screen such as sunken wrecks of ships and divers raising treasures or birds-eye views of cities and landscapes.

While the occupants are being treated to the optical illusions on the screen and at the windows of the car body the latter is rocked or tilted fore and aft and also athwartship in imitation of the movement of the car or boat which the same would naturally make in its passage through the water or air. The preferred construction of the mechanism shown in the drawings for effecting this movement of the body is constructed as follows: *G*, *G'* represent two shafts arranged transversely underneath the front and rear parts of the body and journaled in bearings *g* secured to the adjacent parts of the same. One of these shafts, preferably the forward one, is provided on opposite sides of the longitudinal center of the body with two eccentrics or cams *h* *h* which have their high and low parts on different radial lines. The other or rear transverse shaft is provided with but a single eccentric or cam *i* which is preferably arranged centrally relatively to the car body. Each of these eccentrics or cams rests with its underside and on opposite sides of its shaft on a pair of rollers or wheels *j*, *j* which are pivoted on the upper part of a rocking chair, support or saddle *J*. This chair is pivoted at its lower end to a base *k* so as to be capable of oscillating or rocking in a vertical plane lengthwise of the body. During the rotary movement of each eccentric, that part of the body above the same is alternately raised and lowered as the high and low parts of the eccentric successively engage with the rollers of the chair and the latter rocks forward and backward in adapting itself to the varying positions of the eccentric resting upon the same.

When it is desired to rock the body only fore and aft, the front shaft G is held at rest and only the rear shaft G^1 is turned whereby the rear part of the body is alternately raised and lowered by the rear central eccentric i . When it is desired to only rock the body sideways, the rear shaft G^1 is held stationary and only the front shaft is turned, causing the high and low parts of the front pair of eccentric h, h to alternately engage their chairs and thus successively raise and lower opposite sides of the body. If desired, both transverse shafts may be rotated at the same time, whereby the body will be rocked fore and aft and also sideways at the same time. By stopping the rear shaft G^1 while the highest part of its eccentric is in engagement with its chair, the rear part of the body will be held in a raised position and give the occupants the impression that the car is diving or descending, while upon bringing the rear shaft to rest while the low part of its eccentric is in engagement with its chair the effect of ascending is produced. By arresting the movement of the front transverse shaft while one of its eccentrics has its high part in engagement with its chair and the companion eccentric has its low part in engagement with the respective chair, the car body may be retained in a laterally inclined position, thereby imitating listing of a boat. It will thus be observed that by controlling the movements of the front and rear eccentrics the various effects of moving straight ahead and descending or ascending may be produced in imitation of the movements of a submarine boat or air-ship through tranquil water or air and the body may also be rocked backwards and forwards and sideways in imitation of the movements which would be experienced by a boat or air ship moving through stormy water or air.

Various means may be employed for driving the front and rear transverse shafts, that shown in the drawings, for example, being constructed as follows: L represents a driving shaft journaled lengthwise on the underside of the car body at about the center thereof and driven by gearing l from a motor M secured to the adjacent part of the car. This motor is preferably an electrically operated one but if desired any other suitable type of motor may be employed. N, N^1 represent front and rear intermediate shafts which are journaled lengthwise on the underside of the car body and which form parts of the means for transmitting motion from the driving shaft to the transverse shafts. Each of these intermediate shafts may be coupled with or uncoupled from the driving shaft by means of a clutch head O splined on the respective intermediate shaft and provided with teeth which are movable into and out of engagement with teeth on a clutch head p secured to the adjacent end of the driving

shaft. At its front end the front intermediate shaft is operatively connected by a worm q and worm wheel q^1 with the front transverse shaft and the rear intermediate shaft is in like manner connected by a worm r and worm wheel r^1 with the rear transverse shaft. By means of these clutches either or both of the transverse shafts may be coupled with the motor for producing the motions and effects described. When the motor is disconnected from both transverse shafts and runs idly, the vibration thereof produces the effects of the propeller of a submarine boat or airship when moving forward under normal conditions.

In order to control the car and prevent the same from moving lengthwise bodily while rocking fore and aft the car body is provided with one or more pins or rollers s which engage with vertical slots or guideways s^1 formed in standards S which are secured at their lower ends to the stationary support or foundation. These guideways are of sufficient height to permit the requisite vertical movement at the sides of the car body and are preferably extended upwardly through openings t in the bottom of the car body and concealed within the body by housings or casings T arranged above these openings. While permitting free sideways rocking motion of the car body the guide standards S and the roller s engaging with the slots thereof prevent longitudinal displacement of the car. At opposite sides the car body is provided with anti-friction rollers or bearers u which engage with the inner-sides of the standards S and serve to steady the body during its transverse rocking movement.

For the purpose of permitting the eccentrics to engage properly with the rollers of their chairs during the sideways tilting movements of the car body the face of each of these eccentrics is curved convexly so as to form part of a sphere and the periphery of the rollers j is curved concavously to correspond with the eccentric, as shown in Figs. 4 and 5.

By the aid of a lecture describing the various scenes and experiences during the imaginary passage through the water or air, a very enjoyable, realistic and instructive entertainment may be provided.

I claim as my invention:

1. An amusement device comprising a body, an eccentric for rocking said body fore and aft, and an eccentric for rocking said body sideways, substantially as set forth.
2. An amusement device comprising a body, a single eccentric for rocking said body fore and aft, and two eccentrics arranged with the high and low parts on different radial lines and operating to rock said body sideways, substantially as set forth.
3. An amusement device comprising a body, means for rocking the body fore and

aft, means for rocking the body sidewise, a motor, and means for connecting said motor with either or both of said rocking means, substantially as set forth.

- 5 4. An amusement device comprising a body, a shaft journaled transversely at one end of the body and provided centrally with a single eccentric which operates to rock the body fore and aft, and another shaft journaled transversely at the opposite end of the body and having a pair of eccentrics on opposite sides of the longitudinal center of the body, the high and low parts of said pair of eccentrics being arranged on different radial lines and operating to rock said body transversely, substantially as set forth.
5. An amusement device comprising a body, a shaft journaled transversely at one end of the body and provided centrally with a single eccentric which operates to rock the body fore and aft, another shaft journaled transversely at the opposite end of the body and having a pair of eccentrics on opposite sides of the longitudinal center of the body, the high and low parts of said pair of eccentrics being arranged on different radial lines and operating to rock said body transversely, a main driving shaft, two intermediate shafts geared with said transverse shafts, respectively, and clutches for connecting and dis-

connecting said driving shaft and intermediate shafts, substantially as set forth.

6. An amusement device comprising a body, an eccentric pivotally mounted on said body, and a rocking chair mounted on a stationary support and receiving said eccentric, substantially as set forth. 35

7. An amusement device comprising a body, an eccentric pivotally mounted on said body, a rocking chair pivoted on a stationary support, and rollers pivoted on said chair and arranged to support the eccentric on opposite sides of its pivot, substantially as set forth. 40

8. An amusement device comprising a body, an eccentric mounted on the body and operating to rock the same fore and aft, eccentrics mounted on the body and operating to rock the same sidewise, rocking chairs which support said eccentrics, stationary standards provided with vertical slots, and rollers mounted on the body and working in said slots, substantially as set forth. 50

Witness my hand this 1st day of August, 1906.
